UNITED STATES PATENT OFFICE.

ROBERT P. CRAWFORD, OF ALLEGHENY, PENNSYLVANIA.

BURGLAR-ALARM.

1,065,508.

Specification of Letters Patent. Patented June 24, 1913.

Application filed March 5, 1913. Serial No. 752,221.

To all whom it may concern:

Be it known that I, ROBERT P. CRAWFORD, a citizen of the United States, resident of Allegheny, in the county of Allegheny and State of Pennsylvania, have made a certain new and useful Invention in Burglar-Alarms; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 The invention has relation to burglar alarms, and it consists in the novel construction and combinations of parts, as herein-after set forth.

In the accompanying drawings, illustrating the invention, the numerals 1 and 2 designate the upper and lower sashes of a window, to which the invention is shown as applied, 3 designates a plate attached to the window frame preferably by screws 4, 4. 20 Secured to this plate preferably by screws 5, 5, is a box 6, open at its top 7. Above said box and separated therefrom by an interval, a block 8 is secured to said plate, preferably by screws 9, 9, said block having a longitudinal recess 10, open at its lower end at 11, and terminating at its upper end in a shoulder 12. Above said recess the upper portion of said block is provided with a longitudinal slot 13, open at its upper end 25 at 14 and open at its outer side at 15, said slot being separated from said recess by an intermediate portion 16 of the block, having a longitudinal aperture 17 wherein works a longitudinally slidable plunger 18, 30 said plunger also working in said recess and in said slot. This plunger is provided at its lower end with a head 19, located and working in the recess 10, and surrounding the plunger between the head thereof and said 35 shoulder is a coiled spring 20. A cartridge carrying block 21, is hinged at 22, in the interval between said box and said block, the hinged block having a longitudinal aperture 23 designed to receive a blank cartridge 24, which is centered or alined with respect to said plunger. When the cartridge is placed in position in said block, or when the discharged cartridge is to be removed and replaced by a new one, the block is 40 turned upon its hinge to one side, as shown in dotted lines, Fig. 3, out of line with the

box 6 and block 8. The cartridge being inserted in position, the hinged block is turned back to normal position with its lower surface in supporting engagement with the upper portion of the box 6, thus preventing sagging of the block upon its hinge and bracing it against the discharge of the cartridge.

In setting the alarm, the plunger is raised against the tension of its spring, by means of the handle projection 25, which works in the slot 13 and projects without the open side thereof, and in order to retain the plunger temporarily in raised position a hinged latch 26, pivoted intermediately of its length at 27 to the block 8 and located in the slot 13 thereof, is engaged at the lower outturned end 27 of one arm thereof with the upper shoulder 28 of a notch 29 of said plunger, the upper inturned end 30 of the other arm of said latch being engaged with a longitudinal slot 31^a of one arm of a lever 31, fulcrumed intermediately of its length at 32 to one of the window sashes, the other arm of said lever having a hook end 33 with which a lateral pin 34 of the other window sash has engagement. In this way upon movement of either sash to open the window at top or bottom, the lever 31 will be swung upon its fulcrum 32 or upon the pin 34 as a center, depending upon which sash is moved, to turn the latch upon its hinge and release the latch from the plunger, which will at once fall, under the influence of its spring, and set off the cartridge, the discharge of which is received in the box 6. When the plunger is raised the latch has automatic engagement therewith through the medium of the spring 26.

45 The handle projection 25 is designed, upon the fall thereof with the plunger, to make the electrical connection between two contacts, 35, 35, and complete the circuit of which an electrical bell 36 forms a part, 50 said bell being rung at the same time that the cartridge is discharged.

Having thus described my invention, what I claim as new and desire to secure by Letters Patent is:

1. In a burglar alarm, the combination of a carrier, a plunger working therein provided with a shoulder, a latch device having engagement with said shoulder to temporarily retain the plunger in raised position, 55 a lever adapted for connection with one of the window sashes having operative engage-

ment with said latch, and means adapted for connection with the other window sash having operative engagement with said lever.

5. 2. In a burglar alarm, the combination of a carrier, a plunger working therein provided with a shoulder, a pivoted latch having engagement with said shoulder, a lever having a fulcrum intermediately of its 10 length adapted for connection with one of the window sashes and having operative engagement with said latch, and means adapted for connection with the other window sash having operative engagement with said 15 lever.

3. In a burglar alarm, the combination of a carrier, a plunger working therein provided with a shoulder, a pivoted latch having an outturned end engaging said shoulder, a lever having a fulcrum intermediately of its length adapted for connection with one of the window sashes and provided with a slotted end portion having operative 20 engagement with said latch, and a pin 25 adapted for connection with the other window sash having operative engagement with said lever.

4. In a burglar alarm, the combination of a carrier, a plunger working therein provided with a shoulder and a handle projection, a latch device having engagement with said shoulder, a lever adapted for connection with one of the window sashes having operative engagement with said latch, means 30 35 adapted for connection with the other win-

dow sash having operative engagement with said lever, a cartridge-carrying block in line with said plunger, and electrical contacts having engagement with said handle projection, and means in connection therewith for ringing an alarm. 40

5. In a burglar alarm, the combination of a carrier having at its lower end an open-top box, a plunger-carrying block having a lower longitudinal recess, an upper longitudinal slot open at one side, and an intermediate portion provided with an aperture, a plunger working in said aperture, in said recess and in said slot and having a shoulder and a lower head working in said recess, a 50 coiled spring surrounding said plunger and located between said head and the upper wall of said recess, said plunger having a handle projection extending through the open side of said slot, a hinged cartridge-carrying block between said box and the plunger-carrying block, a latch having engagement with said shoulder, a lever adapted for connection with one of the window sashes having operative engagement with said latch, and means adapted for connection with the other window sash having operative engagement with said lever. 55

In testimony whereof I affix my signature, in presence of two witnesses.

ROBERT P. CRAWFORD.
